UNITED STATES PATENT OFFICE.

RICHARD D. KIMBALL, OF BOSTON, MASSACHUSETTS, ASSIGNOR TO THE KIMBALL AUTOMATIC CAR HEATING COMPANY, OF PORTLAND, MAINE.

SYSTEM OF HEATING CARS BY STEAM AND HOT WATER.

SPECIFICATION forming part of Letters Patent No. 416,844, dated December 10, 1889.

Application filed July 2, 1888. Serial No. 278,786. (No model.)

To all whom it may concern:

Be it known that I, RICHARD D. KIMBALL, of Boston, in the county of Suffolk and State of Massachusetts, a citizen of the United States, have invented a new and useful Improvement in a System of Heating Railway-Cars by Steam and Hot Water, of which the following is a full, clear, and exact description, reference being had to the accompanying drawings, forming a part of this specification, in explaining its nature.

The invention relates to the system of heating railway and other cars which employs steam supplied from the locomotive or other central or common source of supply; and its object is to obtain the greatest efficiency from a given quantity of steam by using in connection with the pipes for the steam-distribution other pipes connected with the steam-pipes, and adapted to receive therefrom the water of condensation while in a heated condition, whereby the heating capacity of the steam is supplemented by the heating capacity of the water condensed from the steam.

I carry my invention into effect by using, in addition to the ordinary pipes for maintaining steam-circulation in the cars, additional pipes, preferably of larger bore, arranged to receive the hot water formed by condensation of the steam from the steam-pipes or pockets arranged therein to receive it, and to cause it to be circulated throughout the car, thereby obtaining, in addition to the amount of heat given off by the circulation of the direct steam, the heat caused by the circulation of the hot water of condensation, which for heating purposes is preferable to steam.

There are many ways by which my invention may be carried into effect, and in the drawings I have illustrated but one of them.

Referring to the drawings, Figure 1 is a view in side elevation of a car having the features of my invention, portions of one side being removed to show the pipes and connections of the system. Fig. 2 is a view in horizontal section of a car, taken immediately above the pipes of the system. Fig. 3 is a view in elevation, and Fig. 4 is a plan, of sections of the pipes enlarged. Fig. 5 is a view

to illustrate one form of connection between the steam-pipe and the hot-water pipe of the system. Fig. 6 is a plan view thereof.

a represents the main steam-supplying pipe, which preferably is arranged below the car midway its width, and which has at each end a flexible tube and coupling *a'*, whereby it is connected with the main pipes of the next cars in order. From this pipe, at each end of the car, there extends a cross-pipe *a''*, the ends of which extend upward through the flooring of the car and connect with the steam-distributing pipes *a³*, and I have represented this connection as made through a trap *B*. This trap affords or provides a pocket for the water of condensation, and also for the connection with the distributing-pipes *b* of the hot-water distribution, and there may be similar pockets and traps at the other ends of the steam-distributing pipes *a³*, and in any other places covered by them. These pockets or traps discharge their contents into the hot-water-distributing pipes *b*, and this may be accomplished automatically or by hand. I have illustrated as one means of making a connection automatically a thermostatic trap *C*, which comprises a casing *c*, divided by a horizontal diaphragm *c'* into the receiving-chamber *c²* and the discharge-chamber *c³*. The upper chamber *c²* connects with the steam-distributing pipes and the hot water from the condensation of steam flows from the steam-pipes into this chamber, which makes a pocket or reservoir for receiving it, and it automatically escapes from said chamber through the passage *c⁴* in the hollow valve *c⁵*, the lower edge of which is adapted to be brought in contact with the seat *c⁶*, upon the expansion of liquid in the chamber *C'*, acting through the flexible diaphragm, due to the presence of live steam in chamber *c²*. When the chamber is partially filled with water, the valve-seat drops from the valve to form a narrow passage which permits the hot water to flow through the passage *c⁴*, and holes or openings *c⁷* into a pipe *c⁸* connecting with the hot-water-distributing pipe. (See Fig. 5.) I would say, however, that I do not confine myself to this particular form of connection between the steam-distributing and hot-water-distrib- 100

utting pipes, but may use any other automatic device or connection.

The hot water is held in the hot-water pipes by a thermostatic or other trap or by cocks.

- 5 I prefer to use at the end of the hot-water pipe the form of thermostatic trap above specified to check or keep back the water in the hot-water pipe. The trap of this character can be used at the outlet of the hot-water
10 pipe, which is the discharge-pipe in this system, because it is never subjected to extreme heat and pressure from the steam, as is the case in systems now in use. Therefore the discharge - trap at the outlet of the hot-
15 water pipe may be opened so as to maintain a constant flow of water at that point at any desired temperature, and when so set it is not liable to freeze. Of course, the hot-water pipe may have no trap to the outlet; but I consider
20 it advisable to locate one there. It will be seen that in any method of car-heating by steam heretofore used, the circulating-pipes used for the steam-circulation have been the only medium whereby the condensation has
25 been gotten rid of, as the condensation in car-heating is very rapid. Particularly in the rear car of the train the condensed water is cooled rapidly in the steam-pipes, thereby obstructing the steam-passage and greatly de-
30 laying the heating of the car. In this system the water is entirely removed from the steam-circulating pipe and contained in the water-pipes below until it has parted with its heat, and is then discharged, thus allowing the cars
35 to be heated very quickly and without appreciable waste of heat. This results in providing the utmost economy possible by use of all the available heat from both steam and water; also, in the rapid heating of the cars because
40 of the perfect removal of the condensed water from the steam-pipes; also, in the greatly-reduced liability of freezing at the outlet of

the discharge-pipe, as a constant flow of water can be maintained at that point by the use of a thermostatic valve, without waste.

45 The advantages arise, first, from the economy in the use of a given amount of steam resulting from it, and, second, from the increased heating effect obtained from a given quantity of live steam.

50 Having thus fully described my invention, I claim and desire to secure by Letters Patent of the United States—

1. The combination, in a system for heating cars by steam and hot water, of one or more 55 steam-distributing pipes, one or more hot-water-distributing pipes, and an automatic discharging device for discharging the condensed steam from the steam-distributing pipe or pipes to the hot-water-distributing 60 pipe or pipes, substantially as described.

2. The combination, in a system for heating cars by steam and hot water, of one or more steam-distributing pipes, one or more hot-water-distributing pipes, a discharging-connection 65 containing an automatic valve or device between the steam pipe or pipes and the hot-water pipe or pipes for discharging the condensed steam from the steam-pipes into the hot-water pipes, and an automatic valve at 70 the outlet of the hot-water pipe, substantially as described.

3. The combination, in a system for heating cars, of one or more steam-distributing pipes, a hot-water-discharge pipe connected 75 therewith and by means of an automatic valve, said valve, and an automatic valve at the outlet of the hot-water pipe, as and for the purposes described.

RICHARD D. KIMBALL.
